INVENTOR
Pontus Ostenberg
BY John A. Alasmith
HIS ATTORNEY

UNITED STATES PATENT OFFICE.

PONTUS OSTENBERG, OF LOS GATOS, CALIFORNIA.

IMPULSE-STARTER.

1,383,480.

Specification of Letters Patent.

Patented July 5, 1921.

Application filed November 15, 1918. Serial No. 262,656.

To all whom it may concern:

Be it known that I, PONTUS OSTENBERG, a citizen of the United States, and resident of Los Gatos, in the county of Santa Clara and State of California, have invented certain new and useful Improvements in Impulse-Starters, of which the following is a specification.

This invention relates to impulse starters used in conjunction with electric generators, especially of the high tension type, to generate a hot spark upon the first revolutions of the generator.

One object of this invention is to provide a device of the character indicated that will be simple in form, construction, application and operation. Another object of the invention is to provide a device of the character indicated wherein the driven member and driving member themselves provide the stop and tripping elements respectively and wherein a simple and novel means is provided for automatically rendering the said stop inoperative when the members are driven at high speed and automatically returned to an operative position when said members slow down to a stop.

With these and other objects in view, the invention consists in the new and novel construction, provision, formation, combination and relative arrangement of parts, members and features as hereinafter described, shown in the drawings and finally pointed out in the claims.

35 In the drawings:—

Figure 1 is a vertical, transverse sectional view of my improved impulse starter.

Fig. 2 is a sectional view on line 2—2 of Fig. 1.

40 Fig. 3 is a sectional view on line 3—3 of Fig. 1.

Figs. 4—5 and 6 are detail illustrations of a portion of the driven member and the detent of my device provided with a stop and novel means for preventing the detent from engaging said stop when the members are rotated at high speed.

Fig. 7 is a detail illustration of a portion of the driven member of my device provided with a stop and having a novel form of detent operatively positioned with relation thereto.

Fig. 8 is a detail illustration of a portion of the driven member of my device provided with a novel means for preventing a detent

from engaging the stop when the member is rotated at high speed.

Fig. 9 is a detail illustration of a portion of the driven member and the detent of my device provided with a stop and novel means for preventing the detent from engaging said stop when the members are rotated at high speed.

Fig. 10 is a detail illustration of a portion of the driven member of my device provided with a novel means for preventing a detent from engaging the stop when the member is rotated at high speed.

Fig. 11 is a vertical transverse sectional view of another embodiment of my invention.

Fig. 12 is a sectional view on line 12—12 of Fig. 11.

Similar characters of reference indicate similar parts throughout the several views.

Referring now more particularly to the drawings, 1 is a portion of a magneto and 2 is the magneto shaft having driven member 3 fixedly mounted thereon. Member 3 is provided with a sleeve 4 to engage shaft 2 and an outwardly projecting flange on its outer edge as indicated at 5, the said flange 5 having a notch or stop formed in its outer circumference as shown at 6.

At 7 is shown the driving member of substantially the same proportions as member 3 and having an inwardly directed sleeve 8 revolubly mounted on sleeve 4, the outer circumference of member 7 being cut away as at 9 to form cam 9^a for the purpose hereinafter described. The said member 7 is held in position by a nut 10 screwed on to the end of shaft 2. Outwardly projecting flange 5 and inwardly projecting sleeve 8 form a circular chamber 11 provided with a dividing member 12 set in flange 5 of member 3. A lug 13 projects into chamber 11 from the inner surface of member 7 of which it is a part and a short buffer spring 14 is positioned between members 12 and lug 13, and a longer compression spring is inserted in chamber 11 as shown at 15.

Mounted upon magneto 1 by pivot 16 is a detent 17 having an inwardly projecting head 18 adapted to engage stop 6 in flange 5. These parts may be inclosed in a suitable casing as 19.

In operation, when driving member 7 is turned in the direction of the arrow member 3 is held immovable by the engagement

of detent 17 with stop 6. As member 7 revolves lug 13 compresses spring 15 until cam 9^a engages head 18 on detent 17 and forces it out of stop 6, the said head 18 being made wide enough to ride upon the outer circumferences of both members 3 and 7. The moment the disengagement of the detent 17 is effected spring 15 relaxes and throws member 3 and the parts attached thereto suddenly forward until the buffer spring 14 contacts with lug 13 whereupon both members 3 and 7 revolve together. The detent is comparatively light and an appreciable length of time is required for 15 the head 18 to fall into engagement with stop 6, therefore when members 3 and 7 are revolving at high speed the head 18 rides over stop 6. When the said members slow down to a stop the head 18 readily falls into 20 engagement with stop 6 and is automatically set into an operative position. The reference 17^a in Fig. 3 indicates the position assumed by the detent 17 when cam 9^a has reached the position 9^b.

25 In Fig. 4 one shoulder of stop 6 is shown cut away as at 20 so that head 18 of detent 17 may even drop slightly as it passes over said stop without engaging the same.

In Fig. 5 the stop 6 is shown cut straight 30 away from its engaging shoulder and the detent 17 is connected to a pin 21 in magneto 1 by a light reed 22 fitting into the end thereof. A second light reed 23 is connected to pivot 16 and carries a boss 24 upon its 35 free end which rests lightly against the outer circumference of member 7. Boss 24 is in constant contact with the periphery of member 7 and exerts a constant but slight tendency to overcome the balancing effect of 40 member 22 and the inertia of the disengaged detent and throw said detent into engagement with stop 6. The result is that the said detent is caused to engage stop 6 at each revolution of the revolving members 45 until sufficient speed has been acquired by them to maintain the detent in an inoperative position, but when the members again slow down the detent is caused to engage the stop and this action is positive in what- 50 ever position the device may be placed.

In Fig. 6 a boss 25 is formed upon the circumference of member 3 adjacent stop 6 so that when said member is revolving rapidly the head 18 of detent 17 first rides up on 55 boss 25 before passing over stop 6 thereby permitting the said detent to drop slightly without engaging the said stop.

Fig. 7 illustrates a chamber 26 formed by a vertical enlargement of casing 19 and containing a detent 27 freely movable therein, the head 18 of said detent operating in conjunction with stop 6 as hereinbefore described.

Fig. 8 shows the stop 12 formed with a 60 chamber 35 formed therein and tapering

outwardly to the circumference of member 3 and intersecting stop 6 and containing a freely movable member 36. When member 3 is revolved at high speed member 36 is thrown outwardly to close the circumferential opening of chamber 35 and thereby prevents the engagement of detent 17 with stop 6. 70

Fig. 9 shows detent head 18 beveled as at 75 37 so that said head will easily ride over the stop 6 when member 3 is revolved at high speed. A balancing arm 38 is also here shown as depending from pivot 16, the same being slightly lighter than detent 17 and head 18 so as to render said detent 17 more 80 delicate in operation.

Fig. 10 shows a portion of the circumferential surface of member 3 cut away as at 39 to form a rise 40 sufficient to cause detent 17 to clear stop 6 when said member 3 is 85 rotating at high speed.

Figs. 11 and 12 illustrate another embodiment of my device in which a spring 28 is connected directly to members 3 and 7, a lug 29 being fixed in member 3 and a 90 pin 30 in member 7 normally in engagement with each other but separated during the forward movement of member 7 and before the disengagement of detent 17 from stop 6. In this embodiment a freely swinging arm 95 31 is pivoted at 32 in chamber 11 and provided with an outwardly extending head 33 adapted to move into and fill slot 34 formed in flange 5 of member 3 and intersecting stop 6. When member 3 is revolved at high 100 speed the centrifugal force throws head 33 outwardly into slot 34 and fills the same so that the detent cannot engage stop 6. When the rotating member 3 slows down to a stop the arm 31 falls inwardly by its own 105 weight thereby permitting detent 17 to engage stop 6. The reference 17^b in Fig. 12 indicates the position assumed by the detent 17 when members 3 and 7 are revolving and member 31 is thrown into the position 31^a. 110

It is known that certain devices have been produced wherein an externally and independently mounted detent is used, the same being automatically moved to an inoperative 115 position, but such devices must be manually reset to an operative position, whereas my invention discloses a means for also automatically resetting the detent. In each of the cases hereinbefore described it is apparent that the principal feature involves the provision of some means co-operating with the circumferential surface of members 3 or 7 or both of them whereby the detent is prevented from engaging stop 6 when said 120 members are revolved at fair speed, but permit said detent to automatically engage the stop when said members slow down to a stop. 125

It is pointed out that when a square shoul- 130

dered stop 6 is used as shown in Fig. 2 it is made but slightly wider in cross-section than the head 18 of detent 17, said width being just sufficient to prevent the action of gravity from pulling the said head into the stop when the member 3 is rotated at high speed. The proportional widths of stop 6 and head 18 would be, in this case, the means that coöperates with the periphery of member 3 for the purpose stated.

In Fig. 5 the parts connected to detent 17 and the periphery of member 7 against which lug 24 operates constitute the means which cooperate with the periphery of member 3 for the purpose set forth.

It is understood of course that I do not wish to confine myself to the specific forms herein set forth but to include all variations that may be made within the scope of the appended claims.

I claim:—

1. An impulse starter for electric generators including a driven member having a stop thereon, a driving member yieldingly connected to said driven member, a detent mounted externally of and independently of said members and adapted to automatically engage said stop when said members are

slowly revolved, means operated by said driving member for rendering said detent inoperative, means operated by the peripheral movement of said driven member for maintaining said detent in an inoperative position, and means operatively mounted with relation to said detent to substantially counterbalance the same.

2. An impulse starter for electric generators including a driven member having a stop thereon, a driving member yieldingly connected to said driven member, a detent pivotally mounted externally of and independently of said members and adapted to automatically engage said stop when said members are slowly revolved, means operated by said driving member for rendering said detent inoperative, means operated by the peripheral movement of said driven member for maintaining said detent in an inoperative position, and an arm depending from the pivotal end of said detent for substantially counterbalancing the same.

In testimony whereof I have hereunto affixed my signature this 7th day of November, 1918.

PONTUS OSTENBERG.
